UNITED STATES PATENT OFFICE

99,522

DESIGN FOR A TAP OR SIMILAR ARTICLE

Frank E. Rice, Detroit, Mich., assignor to American Tap-Bush Company, Detroit, Mich., a corporation of Delaware

Application January 27, 1936, Serial No. 60,844

Term of patent 14 years

To all whom it may concern:

Be it known that I, Frank E. Rice, a citizen of the United States and a resident of the city of Detroit, county of Wayne, and State of Michigan, have invented a new, original, and ornamental Design for a Tap or Similar Article, of which the following is a specification, reference being had to the accompanying drawing, forming a part thereof.

In the drawing:

I claim:

The ornamental design for a tap or a similar article as shown.

FRANK E. RICE.
